UNITED STATES PATENT OFFICE.

JOSEPH O'CONNELL AND HAROLD HAMILTON KERR, OF KENSINGTON, VICTORIA, AUSTRALIA.

CAN CLEANING AND DRYING APPARATUS.

Application filed March 25, 1925, Serial No. 18,116, and in Australia September 27, 1924.

This invention has been devised to provide improvements in or relating to apparatus for cleansing and drying hollow articles especially milk and cream cans, and is particularly useful for cleansing and drying milk cans, and the invention will be described herein in reference thereto, but it is to be understood that its use is not limited thereto, as it may be employed for cleansing and 10 drying other hollow articles.

The object of the invention is to provide apparatus to carry out in sequence and whilst the grid or spider is stationary, operation of the washing, cleansing, rinsing 15 (to remove the cleansing agent) and the drying of the can.

Another object of the invention is to provide apparatus whereby the washing, cleansing and drying operations are greatly facilitated during the movements of the grid or spider hereinafter referred to, and by doing so reducing the period of operations to a minimum.

Another object of this invention is to provide apparatus to cause as the grid or spider rotates and reaches a certain point, the operation of apparatus controlling the washing, cleansing of the interior of the can, removal of the cleansing agent and the drying 30 of the can.

Another object of this invention is to provide apparatus to enable the fats and other foreign matter to be removed from the articles cleansed and to be caught and discharged from the washing solution.

Another object of this invention is to provide apparatus to provide a chamber through which air circulates, during which it is raised in temperature for drying purposes by action of the heat imparted from the hot washing solution.

Another object of this invention is to provide apparatus to enable the cleansing, washing, rinsing and drying agents to be injected under pressure into the can and other parts.

Another object of this invention is to provide apparatus of the class set forth, wherein the entry of the drying agent into the

can is greatly facilitated. Provision is also made wherein water is condensed within the tank to provide a rinsing agent, and provision is also made whereby the operations in the respective compartments can be observed during the rotary movement of the 55 grid or spider hereinafter referred to.

In order that our invention may be the more easily understood, reference will be made to the accompanying drawings in which—

Fig. 1 is a rear view of a tank and shell partly in section and apparatus hereinafter described.

Fig. 2 illustrates the driving and actuating mechanism on an enlarged scale.

Fig. 3 is a sectional plan view of the shell and tank with the cleansing, rinsing and other apparatus disposed therein, some of the parts of the actuating mechanism being removed for sake of clearness.

Fig. 4 shows a sectional plan view of a shell with a rotary grid or spider disposed therein.

Fig. 5 illustrates a partial plan view of the grid or spider drawn to a large scale.

Fig. 6 illustrates a sectional elevation of the central portion of the grid or spider and its supporting hollow pillar and vertical shaft or post.

Fig. 7 is a view of the lower spray pipes and nozzles discharging the washing liquid.

Fig. 8 illustrates an angular shaped arm disposed in the tank and fixed to catch and direct the scum floating on the washing liquid within the tank to an outlet positioned on the wall of same.

Fig. 9 illustrates the discharge chute at the outlet referred to in Fig. 8.

Fig. 10 shows the manner of attaching and holding the lower edge of the shell to the top edge of the tank.

Fig. 11 is an enlarged sectional view of the means employed to impart the necessary rotary movement to the washing liquid within the tank.

Fig. 12 is a side elevation of a vertical operating fork supporting a shaft with cam

actuating a valve to supply steam to a jet within the tank for cleansing purposes.

Fig. 13 is an enlarged sectional view of a rotary grid or spider stationary at a station and within a compartment provided in a fixed shell, the spring controlled holding arm for lid of the can being shown in the compartment.

Fig. 14 is a front view drawn to a small scale of the tank and shell with certain parts of the apparatus omitted for sake of clearness and illustrating an opening in the shell providing the station at which the can and lid are deposited on the rotary grid or spider for treatment and removed therefrom after travelling around and within the shell, during which they are cleansed and dried.

Fig. 15 illustrates a wall of a compartment showing the strips of rubber herein-after referred to.

Fig. 16 is a sectional view of a steam manifold.

Fig. 17 is a view showing an actuating handle with tripping dog and belt shifter, a return actuating spring and wheel with bite referring thereto, also being illustrated.

Fig. 18 illustrates an outer disposed vertical operating and supporting fork herein-after described.

Fig. 19 illustrates the construction of a holder to which each of the air pipes is fixed.

Fig. 20 is a view of a wire gauze filter for the washing liquid and which is disposed within the cylinder adjacent to the pump at the rear of the tank whilst

Fig. 21 is a sectional view of the lower portion of the tank showing an air chamber therein, the air forcing fan being illustrated by dotted lines within a casing disposed outside the tank and fixed to a base plate.

Fig. 22 is a sectional view of an observation window.

In our invention we provide a preferably circular tank 1 (Fig. 14) of suitable dimensions and having disposed at its centre a vertical shaft or post 2 whose lower portion is within a hollow pillar 3 (Fig. 6) fixed to the floor 4 of the tank 1. The shaft or post 2 is held stationary by means of screw threads 5 and 6, the former engaging a female thread provided in the base block 7 fixed in an air chamber herein-after described. The thread 6 engages a female thread of the nut 8, which when screwed home, rests upon the plate 9 at the top of the pillar 3.

Resting and rotating on the surface of the nut 8 is a circular flange or plate 10, integral with the rotary sleeve 11 having upper and lower bush bearings 13 and 14 respectively, for the central and upper portions of the shaft or post 2, disposed in such sleeve 11 whose top is reduced in diameter to provide a shoulder 15 for supporting the roof 16 of a fixed shell 17 herein-after described.

Also integral with the sleeve 11 are a number of vertical wings 18 to which are fixed division walls 19 (Figs. 4, 13, and 14) forming the compartments or stations. Attached to the flange or plate 10 are diagonally disposed members 20 laced with the ribs 21 forming a grid or spider and a so-to-speak turntable. Each member 20 is stayed to the respective division wall 19 by a plate 22 (Fig. 13), the length of the members 20 and the division walls 19 of each compartment being such as to permit rotary movement of the grid or spider within the shell 17 at a position preferably a little below the top of the tank 1. The said shell 17 is supported at its top at the centre or adjacent thereto by the sleeve 11, and the lower edges are held by the lugs 23 (Figs. 10 and 14) fixed to the exterior of the tank 1 close to its top edge.

The shell 17 referred to is divided into any number of rotary compartments, five being preferred, and the roof 16 of the shell covers each respective compartment except at the receiving and discharging station. Within each compartment and hinged to the wall 19 is an angle iron arm 24 (Fig. 13) with bent end 25, a spring 26 whose ends are connected to the wall 19 and member 24 respectively is employed to provide the necessary pressure to hold firmly during treatment a lid or other small article on the grid or spider aforesaid.

The grid or spider receives rotary motion by the aid of a circular rack 27 (Fig. 13) fixed to and under the members 20 of the grid or spider, such rack 27 in turn receives motion from a pinion 28 (Fig. 3) mounted on a transverse shaft 29 lubricated by aid of the pipe 30, such shaft 29 running in a horizontal bearing sleeve 31 fixed on the interior of the tank 1, the shaft 29 extending outwardly from the tank and running in a bearing 32 provided in a ribbed plate 33 fixed to the wall of the tank 1 on its exterior. Mounted on the said shaft 29 is the toothed wheel 34 (Figs. 1 and 2) gearing with a pinion 35 mounted on a second shaft 36 running in a bearing 37 provided in the ribbed plate 33. Also mounted on the shaft 36 and adjacent to the pinion 35 are fast and loose pulleys 38 and 39 respectively, receiving motion from the belt 40 which in turn receives motion from a driving shaft 41, conveniently disposed close to the tank 1 preferably at its rear.

The cleansing, washing and rinsing agents are supplied by the aid of pipes having nozzles positioned for the respective purpose in the order desired. The nozzles are set at desired intervals apart to permit each agent being delivered below, and in some instances above according to the station and the requirements thereat, simultaneously entering the can and lid, (not shown). The opera-

tions of two of the agents i. e. supply steam within the respective compartment to remove from the interior of the can any adhesive matter such as cream and also rinse the can and lid, are controlled by cams 42 and 43 respectively. The contour of both cams is such that during their rotary motion they operate a valve as hereinafter described to carry out functions timed according to the stationary position of the can and lid in the respective compartments. Such cams are mounted on the external portion of the horizontal shaft 29, which as stated before runs in the bearing 32 and also in the bearing 44, at the top of the post 45 which is integral with the bridge 46 bolted to the ribbed plate 33 fixed on exterior of the tank 1. The inner cam 42 has disposed on one side a vertical operating fork 47 (Fig. 12) with roller 48 and lower lip 49 which forces downwardly the spindle 50 of a suitable valve at 51 (Figs. 2 and 3) herewith termed the inner valve, whose nut 52 and stuffing box 53 are supported by a bridge 54 fixed to the bridge 46 and post 45, the valve at 51 is in communication with a pipe 55 leading from the steam manifold 56, and entering the tank at 57, whence it is then taken around the wall of the tank to the receiving and discharging station A, where it is bent to provide a length to place it in a position to ensure sufficient steam being ejected from its nozzle 58 into the respective compartment for the purposes required.

The valve at 59 hereinafter termed the outer valve is similar to the valve at 51, and it has also a vertical operating fork 60 (Fig. 18) with roller 61 and a lower lip 61' engaging a spindle 61^a (Fig. 2). One of the members 62 of such fork is much longer than the other extending some distance above the cam 43 and on the top of such extended member 62 a suitable oil dash-pot 63 is disposed, being suspended from the adjustable arm 64, housed in the sleeve 65 integral with the top of the post 45.

The function of the dash-pot 63 is to control the movement of the fork 60 so as to retard the closing of the valve 59, and by doing so allow a quantity of boiling water to flow through the pipe 59^a to the nozzles 66 and 66^a to enter the respective compartment.

The movement of the shaft 29 is controlled by a lever 67 (Fig. 17) secured to the hinged bar 68, by a bolt 69 passing through both, and a block 70 integral with a curved bar 71 fixed to the exterior of the tank 1 and post 45 respectively, the inner end of the hinged bar 68 being provided with a tripping dog 72 engaging a bite 73 in a wheel 74, upon the latter making one revolution. A spring 75 is connected to bar 68 to cause when compressed an outward pull on such bar to enable the trip dog 72 to

spring outwardly and engage the bite 73 on meeting it as the wheel 74 rotates, the action of moving the lever 67 outwardly swings the shifting forks 76 inwardly, and at the same time transfers the belt 40 on to the loose pulley 39, and upon the trip dog 72 engaging the bite 73, the shifting forks 76 move and place the belt 40 on to the fast pulley 38.

The main cleansing agent is preferably liquid caustic soda of a reduced strength, which is placed in the tank 1, and in the sequence of operations is drawn therefrom through a pipe 77 (Fig. 1) with shut off cock 78 into a cylinder 79 with removable strainer 80. This action is carried out by a suitable pump (not shown), within the casing 81, the pump being actuated by the driving shaft 82 receiving motion by the aid of suitable belting 83 shown in dotted lines running on the fast and loose pulleys 84 and 85. The liquid caustic soda is forced by the pump through the pipes 86 and 87 and delivered continuously at strong pressure to discharging spray nozzles 88 and 89 (Figs. 3 and 7). The two former nozzles are placed within the tank at station C and delivers the liquid caustic soda upwardly, simultaneously within the can and lid. The other nozzles 89 (Fig. 14) are placed on the roof 16 of the shell 17 and spray the liquid caustic soda downwardly striking the exterior of the can or lid, the pressure from the nozzles 88 and 89 being such that sufficient force is provided to move the foreign substances and cause them to leave the can and lid. The pressure or force of the solution is adjusted or regulated to provide a compensating effect; i. e., the pressure from the upper nozzle or nozzles 89 prevents the can and lid being lifted by the pressure from the lower nozzle or nozzles 88. The cleansing agent, liquid caustic soda, is maintained within the tank at the desired temperature by passing steam into the tank by the aid of the pipes 90 and 91 (Figs. 3 and 11), constructed to allow continuous entry at a certain point of the liquid caustic soda in a manner to receive impetus from the steam, causing the liquid caustic soda to be discharged from the pipe 91 with such force that the liquid caustic soda is compelled to maintain a circular movement within the tank, and by doing so enable the skimming operations hereinafter described to be performed (see Fig. 3). The construction for the above purpose comprises a bridge 92 to which the tapered end of pipe 90 is connected, such tapered end providing an orifice 93 which delivers the steam into the pipe 91 whose inner end is open to allow continuously the liquid caustic soda to enter from the opening 94 provided by the bridge 92, passing steam into the tank 1. A condenser comprising pipes 94^a (Fig. 3) arranged V-shaped

is connected to the wall of the tank 1 some distance above the floor of same. The steam during its flow through such pipes 94* is condensed and provides boiling water which 5 passes through the valve at 59 and is delivered to the nozzles 66 at station D for rinsing purposes, while the respective compartment is stationary thereat.

The exterior wall of the shell aforesaid 10 has a number of observation windows clamped by wing nut 95. Rubber bands 96 and 97 provide tight joints for the glass 98 and metal parts 99 (see Fig. 22). This construction permits removal of the parts when 15 desired, and at the same time enables a thorough inspection of the respective compartment to be made during operation.

The drying agent preferably consists of 20 hot air, which in the first instance is sucked in through the opening 100 by a suitable fan 101 mounted on the shaft 41 (Fig. 1) and as shown in dotted lines (Fig. 21) operates in a casing 102. The air is circulated through a pipe 103 into a chamber 104 provided at the bottom of the tank 1, and as it 25 circulates within such chamber 104 is raised in temperature by reason of absorption of heat from the hot liquid caustic soda within the tank 1. The hot air passes out of the 30 chamber 104 through duplicate members 106 each having an opening 105 and formed integral with the plate 107 fixed to the floor 108 of the air chamber 104. After passing 35 through the openings 105 the hot air flows upwardly through the pipes 109 screwed into the roof; i. e., the floor of the tank 1, and the hot air as it is discharged from the mouth of the pipes 109 meets the can or lid respectively.

40 As before stated the movement of the grid or spider is controlled by gear comprising fast and loose pulleys 38 and 39 mounted on the shaft 36. The fast pulley 38 is of aluminium, and its lightness reduces its momentum causing an almost instantaneous 45 stop as the respective compartment within the shell reaches the respective station. Where five compartments are employed the rack 27 makes one revolution to five revolutions of the cams 42 and 43.

50 From the above description it will be understood that the cam 42 before referred to operates the steaming supply apparatus to remove cream and other similar adhesive 55 substance from the interior of the can. The other cam 43 operates the rinsing nozzles; this arrangement enables the rinsing to be performed with hot water, and steams the can and lid, leaving them in a clean condition, after which they are subjected to drying by the hot air. The top of each wall 19 60 dividing the compartments is provided with a longitudinal plate of rubber 110 (Figs. 14 and 15) or the like material which is in contact with the ceiling and wall of the shell

17; this arrangement enables a closure of the top of each compartment, but will not prevent rotation of the grid or spider within the shell. Fats and other foreign matter removed from the cans and lids and which float 70 on the surface of the washing solution i. e. liquid caustic soda are moved by the aid of a diagonally disposed arm 111 (Figs. 3 and 8) whose lower edge is submerged in the solution in a manner to catch and direct the 75 substances referred to and discharge them through an opening 112 provided in the tank 1 before referred to.

In operation, steam is supplied to the steam manifold 56 (Figs. 2 and 16), after 80 which the taps 113, 114 and 115 are operated to supply steam to the nozzle 58, steam to the condenser 94*, and steam to the pipe 91 within the tank to heat the liquid caustic 85 soda and simultaneously move and agitate such liquid placed in the tank 1 previous to operations being started. Assuming that a can and lid are in four compartments and the grid or spider is stationary, and the non-occupied compartment is in front of the station A, the driving belt 40 would be running on the loose pulley 39, and upon the attendant placing the can and lid on the grid or spider, face downwardly in the compartment 90 with the arm 24 holding the lid, he operates the lever 67 to disengage the tripping dog 72 from the bite 73, simultaneously with this action the shifting fork 76 transfers the driving belt 40 to the fast pulley 38, resulting 95 in the gear wheels 34 and 35 being brought into action to cause the grid or spider to rotate. Simultaneously with this action the cams 42 and 43 are rotating; i. e., making one revolution, during which the former 100 operates as follows—engages the roller 48, and in doing so forces the vertical fork 47, and with it the spindle 50 of the valve at 51, opening same and allowing steam to pass through the second section of the pipe 55 and thence to the nozzle 58. The steam from 105 the latter enters both the can and the lid. In the meantime, the outer cam 43 also revolves and engages its roller 61 and forces the fork 60 downwardly operating the spindle 61* and opening the valve at 59 to allow the boiling 110 water obtained from the condenser pipes 94* to flow through the second section of the pipe 59* to the jets, 66, 66*, the can being stationary at the station marked D. Previous to 115 the respective can and lid reaching the last mentioned station and after leaving station A, the can and lid have passed stations B and C. At the former station, whilst the grid or spider is stationary, the cream and drips are falling from both, being loosened by the jet of steam from the nozzle 58—when 120 at the station A. On reaching station C the can and lid receives a strong spray of liquid caustic soda, which is supplied continuously both from the lower or upper spray 125

130

nozzles 88 and 89 respectively. This action thoroughly removes any cream adhering to the can and lid, which upon being conveyed to station D both are subjected to a thorough rinsing by boiling water from the nozzles 66 and 66^a. This removes any liquid caustic soda that may have remained in or on the can or lid. Upon the grid or spider making its next movement, it deposits the can or lid 5 at station E where both receive a strong blast of hot air from the pipes 109, and by doing so are dried. The next movement of grid or spider places the now treated can and lid at station A, whereupon they are removed 10 for use, and a fresh can and lid deposited 15 upon the grid or spider for the same treatment.

During the movement of the grid or spider and the cams 42 and 43, the respective compartments have been rotated, and as each function is performed at the respective station, the lever 67 is operated to actuate the forks 76 which transfers the driving belt 40 from the fast pulley 38 to the 20 loose pulley 39 or vice versa.

It will be seen that whilst the grid or spider is stopped to allow removal of the treated can and lid, and a fresh one placed in the compartment, the cans and lids in 30 the other compartments are receiving treatment; this enables the sequence of operations to be carried out promptly and with very little if any loss of time, and by doing so allows a maximum number of cans 35 and lids to be treated within a short period.

Claims:

1. A can cleaning apparatus, comprising a cylindrical tank, a rotary grid-like can support above the tank, means for injecting 40 a cleaning liquid into and onto the cans, said liquid being thereafter collected in the tank, means to impart a rotary movement of the liquid in the tank, and a stationary skimmer, against which the rotating liquid 45 moves, arranged to guide the liquid toward the periphery of the tank.

2. A can cleaning apparatus, comprising a cylindrical tank, a rotary grid-like can support above the tank, means for injecting 50 a cleaning liquid into and onto the cans, said liquid being thereafter collected in the tank, means to impart a rotary movement of the liquid in the tank, and a stationary skimmer, against which the rotating liquid 55 moves, arranged to guide the liquid toward the periphery of the tank, and an aperture in said periphery for the overflow of the liquid in the tank.

3. A can cleaning apparatus, comprising 60 a can support, means for injecting a cleaning liquid into the cans on the support, a cylindrical tank below the support to collect the liquid discharged from the cans after being injected into the latter, a curved conduit open at its ends immersed in the liquid

and arranged eccentrically to the periphery of the tank, means for entraining the liquid in the tank, through the conduit and thereby rotating said liquid, an aperture in the tank for the discharge of the liquid from the latter, and a skimmer for guiding the rotating liquid toward the aperture.

4. A can cleaning apparatus, comprising a cylindrical collecting tank, a housing for the cans mounted above the tank, a rotary grid within the housing for supporting the cans, spray nozzles in the tank for injecting a cleaning liquid into the cans on the grid, a curved conduit open at both ends immersed in the liquid collected in the tank, 75 said conduit arranged eccentrically to the periphery of the latter, and a steam discharge nozzle arranged to inject steam into one end of said conduit whereby the cleaning liquid in the tank is entrained into the conduit and discharged therefrom to impart 80 a circular movement to the liquid in the tank.

5. A can cleaning apparatus, comprising a cylindrical collecting tank, a housing for the 90 cans mounted on the tank, a rotary grid within the housing for supporting the cans above the tank, spray nozzles in the tank and housing for injecting a cleaning liquid into and on the cans carried by the grid, a 95 steam discharge nozzle arranged to inject steam into the cans carried by the grid, a steam manifold for supplying steam to said nozzle, a steam condenser connected with the manifold, a water discharge nozzle in 100 the tank for injecting water into the cans, the tank for injecting water into the cans, a conduit connecting the condenser with the last named nozzle, and valves in the manifold for controlling the flow of steam to the steam discharge nozzle and to the condenser. 105

6. A can cleaning and drying apparatus, comprising a cylindrical collecting tank, a housing for the cans mounted above the tank, a rotary grid within the housing for supporting cans above the tank, a steam 110 manifold, a steam discharge nozzle connected with the latter arranged in the tank below the grid adapted to inject steam into the cans mounted on the grid, spray nozzles in the tank and housing for discharging a 115 cleaning liquid into and on the cans, a condenser connected with the manifold, a water discharge nozzle in the tank connected with the condenser and arranged to inject water into said cans, and means in the tank for 120 injecting heated air into said cans.

7. A can cleaning apparatus, comprising a tank, a housing mounted above the latter, a rotary grid within the housing for supporting the cans, mechanism including a 125 driving shaft for rotating the grid, a steam manifold, a steam discharge nozzle in the tank for injecting steam into the cans on the grid, a steam supply pipe connecting the nozzle and manifold, a condenser connected 130

with the latter, a water discharging nozzle in the tank for injecting water into the cans, a water supply pipe connecting the condenser and water discharge nozzle, valves in the steam and water supply pipes, and means on the driven shaft for actuating the valves.

8. In an apparatus for cleaning cans, a tank, a housing mounted above the latter, a rotary grid within the housing for supporting the cans, an annular rack on the grid, a driven shaft, a pinion on the latter in mesh with the rack, means for driving the shaft, a steam discharge nozzle mounted in the tank, a water discharge nozzle and a condenser within the tank, a steam manifold outside the tank and connected with the condenser, a pipe connecting the steam discharge nozzle with the manifold, a valve in the latter for controlling said pipe, a pipe connecting the condenser and water discharge nozzle, valves in the pipes connecting the nozzles with the manifold and condenser, means operated by the movement of the driven shaft for actuating the last named valves, means for supplying a cleaning liquid to the cans, and means in the tank for imparting a rotary movement to liquid collected in the tank from the cans to facilitate the skimming of the liquid.

9. In an apparatus for cleaning cans, a cylindrical tank, a housing mounted above the latter, a rotary grid within the housing for supporting the cans, an annular rack on the grid, a driven shaft, a pinion on the latter in mesh with the rack, means for driving the shaft, a steam supply nozzle mounted in the tank, a water discharge nozzle and a condenser within the tank, a steam manifold outside the tank, a pipe connecting the steam discharge nozzle with the manifold, a pipe connecting the condenser and water discharge nozzle, valves in the pipes, means operated by the movement of the driven shaft for actuating the valves, means for supplying a cleaning liquid to the cans, an eccentrically arranged conduit in the tank, and an injector nozzle connected with the manifold and arranged to discharge steam into one end of the conduit thereby entraining the cleaning liquid collected in the tank from the cans to heat and impart a rotary motion to said tank liquid to facilitate the skimming of the latter.

10. In an apparatus for cleaning cans, a cylindrical tank, a housing mounted above the latter, a rotary grid within the housing for supporting the cans, radial partitions arranged in the housing movable with the grid and forming separate compartments in the housing for the cans, means for injecting a cleaning liquid into and onto a can in one of the compartments, means for injecting steam into a can in one of the compartments, means

for injecting water into a can in one of the compartments, an air chamber arranged below the tank and adapted to be heated by the contents of the latter, a curved conduit immersed in the liquid of the tank, means to inject steam into the conduit to entrain the tank liquid through the conduit and thereby impart a rotary movement to said liquid to facilitate the skimming of the latter, and means to supply heated air from the air chamber to one of the compartments, and a stationary skimmer against which the rotating liquid moves.

11. In an apparatus for cleaning cans, a cylindrical liquid collection tank, a housing mounted above the latter to receive the cans, a rotary grid within the housing for supporting the cans, means for supplying a cleaning liquid to the cans, a curved conduit arranged eccentrically within the tank and immersed in the liquid of the latter, a steam manifold, and a steam discharge pipe leading from the latter projecting into one end of the conduit and forming an annular opening in said end, whereby steam from said pipe will entrain the cleaning liquid in the tank into the conduit and impart a rotary movement to said liquid to facilitate the skimming of the latter.

12. In an apparatus for cleaning cans, a cylindrical liquid collecting tank, a housing mounted above the latter, a rotary grid within the housing for supporting the cans in the housing, means for supplying a cleaning liquid to the cans on the grid, a curved conduit arranged eccentrically within the tank and immersed in the liquid therein, a steam manifold, and a pipe leading from the latter projecting into one end of the conduit and forming an annular opening in said end, whereby steam from said pipe will entrain the liquid in the tank into the conduit and impart a rotary movement to said liquid to facilitate the skimming of the latter, a condenser mounted in the tank connected with the manifold, a water discharge nozzle mounted in the tank connected with the condenser, and arranged to inject water into the cans on the grid, a steam discharge nozzle connected with the manifold, and arranged to inject steam into the cans, valves in the connection between the nozzles and manifold, means for rotating the grid, and means operated by the rotating means for actuating the valves.

13. In an apparatus for cleaning cans, a tank, a housing mounted on the latter, a rotary grid within the housing for supporting the cans, means for rotating the grid, means movable with the grid for holding the cans on the latter, directly opposed means for injecting a cleaning fluid into the tank and housing in opposite directions into and onto the cans, a nozzle for injecting steam into

the cans on the grid, a steam condenser in the means for rotating the grid for actuating the tank, means for supplying steam to the condenser, a water discharge nozzle connected with the condenser and arranged to

In testimony whereof we have signed our ¹⁰ names to this specification.

- 5 inject water into the cans on the grid, means for controlling the supply of water and steam to the nozzles, and means operable by

JOSEPH O'CONNELL.
